UNITED STATES PATENT OFFICE.

JOHN JOSEPH LINK, OF ST. LOUIS, MISSOURI.

LOCK.

SPECIFICATION forming part of Letters Patent No. 591,479, dated October 12, 1897.

Application filed May 27, 1897. Serial No. 638,331. (No model.)

To all whom it may concern:

Be it known that I, JOHN JOSEPH LINK, a citizen of the United States, residing at the city of St. Louis, in the State of Missouri, have 5 invented a certain new and useful Lock, of which the following is such a full, clear, and exact description as will enable any one skilled in the art to which it appertains to make and use the same, reference being had 10 to the accompanying drawings, forming part of this specification.

My invention relates to a lock, and more particularly to that class of locks known as "latch-locks," in which the lock is operated 15 from one side by a key and from either one or both sides by a knob or knobs.

The objects of my invention are to provide a lock which is simple of construction, to provide means for throwing one of the knobs out 20 of engagement with the lock, to improve the construction of the key-cylinder, and to provide means for giving an alarm when the door is opened.

My invention consists in the various novel 25 features and details of construction which are described in the following specification, and pointed out in the claims affixed hereto.

In the accompanying drawings, which illustrate one form of lock made in accordance 30 with my invention, Figure 1 is a side elevation of the lock, the key-cylinder and half of the casing being removed, and a section of a portion of the door-frame. Fig. 2 is a vertical section on the line 2 2 of Fig. 1, the key-cylinder and the entire casing being in position. Fig. 3 is a section on the line 3 3 of Fig. 1, showing the lock complete and mortised in a door. Fig. 4 is an elevation of the inner door-plate. Fig. 5 is a side elevation of 35 the key-cylinder. Fig. 6 is a longitudinal section of the key-cylinder. Fig. 7 is a view similar to Fig. 6, but showing the key inserted in the cylinder. Fig. 8 is a section on the line 8 8 of Fig. 6. Fig. 9 is a view similar to Fig. 8, 40 but looking in the opposite direction. Fig. 10 is a view showing the surface of the key developed. Fig. 11 is a section on the line 11 11 of Fig. 1, and Fig. 12 is a section on the line 12 12 of Fig. 1. Figs. 6 to 10, inclusive, 45 are on an enlarged scale.

Like marks of reference refer to similar parts in the several views of the drawings.

The casing of the lock is composed of two similar parts 15 and 16. On the part 15 are formed two thickened portions or blocks 17, 55 to which are secured by means of screws 18 two lugs 19, formed on the selvage or edge plate 20 of the lock. On the part 15 is formed a projection 21, having a semicylindrical recess for the reception of a bolt, to be herein-after described. In the projection 21 is a threaded hole 22. On the part 16 is a projection 23 similar to the projection 21 and provided with a hole, through which passes a screw 24, (shown in dotted line in Fig. 2,) 65 which engages with the threaded hole 22, and thus holds the two parts of the casing together. On the projection 21 is an extension 25, which acts as a stop to limit the motion of the bolt in one direction. On the part 15 70 is also formed a stop 26, (best shown in Fig. 12,) which has a lateral extension 27. 29 is a rotary bolt which slides between the projections 21 and 23. On the bolt 29 is an enlarged portion 30, which projects through 75 the selvage 20 and is provided with an inclined face, which is so adjusted as to partially rotate the bolt when it comes in contact with the striking-plate, as is fully described in Patent No. 549,143, granted to me 80 November 5, 1895. The enlarged portion 30 is secured to the bolt 29 by a screw 31, and by loosening the said screw it can be adapted to either a right or left hand door. On the bolt 29 is a downward projection 32, which 85 engages with the stop 25 to limit the forward motion of the bolt and also when in its normal position engages with the stop 26 to prevent the backward motion of said bolt.

33 is a coil-spring, one end of which is secured in the enlarged portion 30 of the bolt 29 and the other in the projection 21. The spring 33 holds the bolt 29 in its normal position, both with respect to its sliding and its rotary motion. On the bolt 29 is formed a 90 substantially U-shaped portion 34. The free end of the U-shaped portion 34 is provided with a rounded part 35 and has formed in it a recess or notch 36, Fig. 11. At the opposite end of the portion 34 is a shoulder 37 95 and at its center a rounded depression 38. Journaled in the parts 15 and 16 and passing between the arms of the U-shaped part 34 is a cylinder 39. On the cylinder 39 are two pro-

jections 40 and 41, which have rounded surfaces and are adapted to engage with the rounded portion 35 and the depression 38, respectively. On the cylinder 39 is also formed 5 a segment of a disk 42, which engages with the recess 36. Passing through the cylinder 39 is a square opening 43.

44 is a small coil-spring, one end of which is attached to the case 15 and the other to the 10 projection 41.

45 and 46 are two side plates, which are held in position by screws or bolts 47, passing through the plate 45 and door 48 and screwing into projection 49 on the plate 46. On 15 the plate 46 is a sleeve 50, through which passes the shank 51 of a knob 52. The shank 51 is held in place by a collar 53 and has formed through it a square opening 54. On the plate 45 is a sleeve 55, through which passes 20 the shank 56 of a knob 57. In the shank 56 are two circumferential grooves 58 and 59, and upon its end is a collar 60, which prevents it from being withdrawn from the sleeve 55.

25 Secured in the shank 56 is a square bar 61, which passes through the cylinder 39 and has at its end a cylindrical portion 62. Pivoted to the plate 45 at points 63 are two plates or strips 64. The upper ends of the strips 64 30 slide in a guide 65 and are drawn toward each other by a small coil-spring 66. The strips 64 are so shaped as to partially surround the shank 56, and by entering one of the circumferential grooves 58 or 59 prevent 35 the longitudinal motion of said shank and attached parts. Passing through the plate 45 and between the strips 64 is a small rod 67, having a flattened head or thumb-piece 68.

Secured on the rod 67 is a small oval piece 40 69, which forces the strips 64 apart when the thumb-piece 68 is turned. On the rod 67 is also secured a cylinder-plate 70, which prevents the strips 64 from slipping off the pivots 63. 71 are stops to limit the motion of the 45 strips 64.

In each of the plates 15 and 16 of the casing is a circular opening 73 for the reception of the key-cylinder.

74 is the shell or case of the key-cylinder. 50 The shell 74 is provided with a flange 75, and its walls are thickened near the end, so as to form an internal flange or shoulder 76 and leave an opening 77 only large enough to easily admit the key. Within the case 74 is a rotary 55 part or barrel 78. Carried by the barrel 78 is a bit 79, which moves in a slot extending almost around the case 74. When the barrel 78 is rotated, the bit 79 engages with a curved lateral arm 80, Fig. 1, on the downward projection 32 of the bolt 29. The barrel 78 is held in place by a disk or short cylinder 81 in the end of the case 74. In the barrel 78 is a circular opening 82 of the same size as the opening 77 in the case 74, in the center of 60 which is a square bar 83. Around the opening 82 and intersecting it are a number, preferably four, of smaller openings 84. In the

center of the openings 84 are still smaller openings 85, and corresponding openings 86 and 87, respectively, are made in the shoulder 70 76 and the disk 81. In each of the openings 85 is a rod 88 exactly the length of the barrel 78. On the rods 88, at varying distances from the ends, are formed collars 89 of such a size as to slide in the openings 84. Around each 75 of the rods 88 is a small coil-spring 90, which normally forces the ends of the said rods into the openings 86 and thus prevents the rotation of the barrel. The key 91 is cylindrical and has in its end an opening for the reception 80 of the square bar 83. Around the key are a number of depressions 92 of such depths that when the key is inserted in the cylinder the rods 88 will be withdrawn from the openings 86, but not projected into the openings 85 87. On the key is a small projection 93, which slides in a corresponding groove 94 in the key-cylinder, and thus insures the proper insertion of the key. On the flange 75 are two pins 94^a, which enter holes 94^b in the casing 90 and thus prevent the shell 74 from rotating. The holes 94^b are made in both sides of the casing, so as to allow the cylinder to be inserted from either side and thus adapt the lock for either a right or left hand door. 95

In order to give an alarm when the door is opened, the lock may be provided with a device like that shown in Fig. 1. An electrical conductor 95 is carried by but insulated from the selvage 20. The conductor 95 extends 100 through and is flush with the face of the said selvage. A conductor 96 is carried by the bolt 29 in such a position that when the bolt is in its normal position the said conductor is out of contact with the conductor 95, but when the bolt is rotated the conductors will be brought in contact. Carried by a plate 97, secured in the door-frame, is a tube of insulating material 98. In the tube 98 is a small metallic rod 99, which is pressed against the 110 end of the conductor 95 by a small coil-spring 100 when the door is closed. Projecting through a slot 101 in the tube 98 is a small rod 102, to which is attached a rod 103, parallel to the rod 99, one end of which will be 115 forced against the plate 97 by the action of the spring 100 when the door is open, and the other end of which will be forced against the rear of the chamber 104, into which the bolt projects if the rod 99 is pressed too far into 120 the tube 98. To the coil-spring 100 is attached one terminal of an electric circuit 105, the other end of which is attached to the plate 97. In the circuit 105 is a suitable source of 125 electrical energy 106 and a bell 107 or other suitable alarm.

The operation of my lock is as follows: When one of the knobs is rotated, the motion is communicated through the bar 61 to the cylinder 39. If the cylinder 39, Fig. 1, is 130 rotated toward the right, the projection 40 comes in contact with the rounded end 35 of the U-shaped part 34 and forces the said part 34 toward the part 15 of the case. This par-

tially rotates the bolt 29 and throws the downward projection 32 away from the part 15, so that it does not come in contact with the main part of the stop 26 and thus leaves the bolt free to move longitudinally. The segment 42 then engages with the recess 36, Fig. 11, and by the further rotation of the knob throws the bolt backward. When the bolt has been thrown far enough back, the projection 32 comes in contact with the lateral extension 27 of the stop 26 and thus prevents any further movement. If the cylinder is rotated in the opposite direction, the projection 41 will force the part 34 toward the case 15 to release the bolt by its contact with the curved portion 38 of the said part 34, after which the segment 42 will come in contact with the shoulder 37 and force the bolt back. Fig. 3 shows the normal position of the part 34, and Fig. 2 its position when it has been moved to release the bolt.

When it is desired to throw the knob 52 (the outside knob) out of operation, the thumb-piece 68 is partially rotated to separate the plates 64 and thus take them out of engagement with the groove 58, and the knob 57 pulled out until the plates 64 fall into engagement with the groove 59. This draws the square part of the bar 61 out of the shank 51 of the knob 52 and allows the knob 52 to be turned without affecting the lock, as the shank 51 simply slides around the cylindrical portion 62.

When the key 91 is inserted in the key-cylinder, the shoulders formed on the key by the cut-away portion 92 come in contact with the collars 89 on the rods 88 and force the rods out of the openings 86 into the barrel 78. If one of the grooves 92 should be too long, the rod 88 upon which it acted would not be forced out of the opening 86, and if too short the end of the said rod would be forced into one of the openings 87. After the key has been inserted in the cylinder and the barrel 78 thus released the key is rotated and with it the barrel. The bit 79 comes in contact with the curved arm 80, Fig. 1, and rotates the bolt 29 to release the same, as hereinbefore described. The bit 79 then comes in contact with the projection 32 and throws the bolt back.

Whenever the bolt 29 is rotated the conductor 96 is brought in contact with the conductor 95, thus completing the circuit through the alarm 107, the current passing along the wire 105, spring 100, rod 98, conductor 95, and conductor 96, from which it passes to the bolt 29, and thence through the metallic parts of the lock to the plate 97, to which the line-wire 105 is attached. When the door is opened, the rod 103 is pressed against the plate 97 by the action of the spring 100 and thus keeps the circuit closed, so as to sound the alarm. If the rod 99 is pressed back to stop the alarm, it will nearly always be pressed back too far, in which case the rod 103 will

come in contact with the part 104 and thus complete the circuit.

The lock can readily be changed from a right to a left hand lock by loosening the screw 31 and rotating the portion 30 of the bolt half a revolution and withdrawing the key-cylinder from the casing and replacing it from the opposite side. In securing the lock in the door the plate 45 is always placed on the inside face of the door.

Having fully described my invention, what I claim as new, and desire to secure by Letters Patent of the United States, is—

1. In a lock, a rotating bolt, dogging devices normally locking said bolt against longitudinal motion, a substantially U-shaped member carried by said bolt, a rotary member situated between the arms of said U-shaped member, devices carried by said rotary member and acting upon said U-shaped member to rotate said bolt to release the dogging devices therefrom and to throw said bolt, and means for actuating said rotary member.

2. In a lock, a sliding bolt, a rotary member provided with means for throwing said bolt, a stationary casing for said rotary member, suitable rods carried by said rotary member and parallel to its axis, openings in said casing for the reception of the ends of said rods, springs normally pressing said rods into said openings, the forward ends of said pins or rods being covered by said stationary casing, and suitable projections on said pins or rods for engagement with a key.

3. In a lock, a sliding bolt, a rotary member provided with means for throwing said bolt, a stationary casing for said rotary member, rods or pins carried by said rotary member, a set of openings in said casing, springs normally pressing said pins into said openings, a second set of openings in said casing and into which said pins will be pressed if they are moved more than a predetermined amount from their normal position, the forward ends of said pins or rods being covered by said stationary casing, and suitable projections on said pins for the engagement of a key.

4. In a lock, a sliding bolt, a rotary member provided with means for throwing said bolt, a stationary casing for said rotary member, an opening in said rotary member for the reception of a key, pins or rods carried in said rotary member around said opening, the forward ends of said pins or rods being covered by said stationary casing, projections adapted to be engaged by a key carried by said pins and extending into said opening, and openings in said casing into which said pins will project to lock said rotary part against motion except when said pins are in a predetermined position.

5. In a lock, a sliding bolt, a rotary member provided with means for throwing said bolt, a stationary casing for said rotary mem-

- ber, an opening in said rotary member for the reception of a key, pins or rods carried in said rotary member around said opening, the forward ends of said pins or rods being 5 covered by said stationary casing, projections adapted to be engaged by a key and carried by said pins or rods and extending into said opening, openings in said casing into which said pins project to lock said rotary member 10 against motion except when said pins are in a predetermined position, and a central pin or bar carried by said rotary member and determining the distance to which the key can be inserted into the lock.
- 15 6. In a lock, a lock-case carried by a door, a plate of conducting material carried by the door-frame and normally in contact with said lock-case, a suitable conductor carried by but insulated from said lock-case, means for

placing said conductor in electrical contact 20 with said case, a spring-actuated contact normally pressed against said conductor, a circuit provided with a suitable source of electrical energy and an alarm connecting said spring-actuated contact and said plate of conducting material, and means for placing said spring-actuated contact in electrical communication with said plate of conducting material when said spring-actuated contact is released by the opening of the door. 25

In testimony whereof I have hereunto set my hand and affixed my seal in the presence of the two subscribing witnesses.
